J. DUBROVIN

COMPRESSOR FOR REFRIGERANTS

Filed Jan. 12, 1925

FIG. 1.

FIG. 2.

UNITED STATES PATENT OFFICE.

JOHN DUBROVIN, OF CHICAGO, ILLINOIS, ASSIGNOR, BY MESNE ASSIGNMENTS, TO UNIVERSE CORPORATION, OF CHICAGO, ILLINOIS, A CORPORATION OF ILLINOIS.

COMPRESSOR FOR REFRIGERANTS.

Application filed January 12, 1925. Serial No. 1,765.

To all whom it may concern:

Be it known that I, JOHN DUBROVIN, citizen of Russia, resident at Chicago, in the county of Cook and State of Illinois, have 5 invented certain new and useful Improvements in a Compressor for Refrigerants; and I do hereby declare the following to be a full, clear, and exact description of the invention, such as will enable others skilled 10 in the art to which it appertains to make and use the same.

My invention relates to a compressor for a normally gaseous refrigerant, and in general to the providing of a unitary appliance 15 or appliance portion free of moving parts and advantageously employed as the head portion of the compressor, which appliance or appliance portion will function simultaneously for accomplishing a number of 20 highly important purposes. One of these purposes is that of providing a storage chamber for the expanded refrigerant and a connection from this chamber for securing an unusually speedy filling of the compressor 25 cylinder, together with a construction whereby sediment is entrapped in this storage chamber and whereby any liquid passing into this chamber will readily be evaporated.

Another important purpose is that of providing an oil separator in the form of a simple chamber adapted to entrap oil from the freshly compressed refrigerant and constructed so as to provide a tortuous path 35 for the compressed refrigerant to facilitate the separation of the oil from the same.

Still another purpose is that of affording an effective interchange of heat between certain cold and hot elements; the cold elements being the expanded refrigerant and the storage chamber cooled by the latter; the hot elements being the compressor cylinder, the freshly compressed refrigerant, the compressing chamber into which the freshly 45 compressed refrigerant is rapidly discharged from the compressor cylinder and from which it gradually issues, and the oil separator chamber. For this latter purpose, my invention provides an arrangement 50 of parts in which certain of these chambers have heat-conducting walls in common with each other, and have wall portions formed

so as to expose surfaces of considerable area to both the hot and the cold refrigerant on opposite sides of these wall portions. It 55 also provides an arrangement of parts in which the same formations which provide a tortuous path for the compressed refrigerant also afford surfaces of relatively large area for facilitating the interchange of heat. 60

Moreover, my invention provides a construction for the above named purposes comprising simple and easily manufactured parts adapted for an easy assembly of the same and designed to permit the separate 65 testing of each part as to its freedom from blow-holes or cracks, before the parts are assembled. Still further and also more detailed objects of my invention will appear from the following specification and from 70 the accompanying drawings, in which—

Fig. 1 is a diagrammatic view of a refrigerating system of a type suitable for employing sulphur dioxide as the refrigerant, in which the compressor is equipped with a 75 head construction embodying my invention.

Fig. 2 is an enlarged central and vertical section through the same head construction and the upper portion of the compressor.

Referring to Fig. 1, this shows a compressor 1 having a vertical cylinder 2 at its upper end discharging through an upper casing 3 into a pipe 4 leading to the usual condenser 5. After being cooled in the condenser, the compressed refrigerant passes 80 through an expansion valve and into a refrigerating coil 7, and then from the latter through the upper portion of the head assembly to the intake pipe 8 which leads to the cylinder of the compressor. 85

In Fig. 2, I am showing the cylinder 2 as having at its upper end an annular seat for a movable disk 9, this disk being normally held down against the seat both by pressure of compressed gas above it and by a spring 90 10. I am also showing the annular bottom portion of the hereafter described oil separator chamber 35 as connected to the crank case of the compressor through pipes 13 and 14 between which a pressure-responsive 95 valve 36 is interposed (after the manner more fully described in the Twardowsky Patent #1,450,122 of March 27, 1923) so that some of the collected oil 100 25 will be re-

2 turned through these pipes into the crank casing whenever the pressure in the latter falls to that for which the valve is adjusted.

In the illustrated embodiment, the top of the compressor cylinder is surmounted by a casting having a downwardly open and substantially cup-shaped portion 15 which carries flanges secured to corresponding flanges on the cylinder by bolts 16. The interior of the cup-shaped formation affords a compression chamber 17 which is normally closed at its bottom by the valve member (or movable cylinder head) 9 and from which chamber the compressed refrigerant issues through a vertical pipe 18 extending downward close to the valve member 9 and opening through the top 19 of the said cup-shaped casting portion. When the compressor is in operation, the spring 10 and the pressure of the compressed gas within the compressor chamber 17 cooperate in resisting a lifting of the valve member 9 until the pressure in the cylinder becomes sufficiently great, after the manner disclosed in the Twardowsky Patent #1,450,122 of March 27, 1923. With a proper adjustment and proportioning of the parts, this occurs when the piston is rather close to the valve member 9, and the rapid forcing of the compressed gas from the cylinder into the compression chamber quickly reduces the compression in the cylinder, so that the connection between the cylinder and the compression chamber is only open for a small fraction of each reciprocating movement of the piston. Then the compressed gas issues gradually from the compression chamber during the next succeeding reciprocation of the piston.

Instead of discharging the issuing compressed gas direct from the pipe 18 into a pipe leading to the usual refrigerant-cooling condenser, I cause the compressed refrigerant first to pass through a chamber in which this compressed refrigerant is somewhat warmed and is separated from such lubricating oil as may have been carried past the piston into the compression chamber and carried out of the latter with the compressed refrigerant through the pipe 18. For this purpose, I provide an outer wall surrounding and spaced from at least a portion of the side wall of the cup-shaped casting 15, this being here shown as comprising a substantially cylindrical wall 20 extending both above and below the top 19 of the said inverted cup-shaped casting and as connected to the side wall of the latter by an annular and substantially horizontal flange 21, so as to form an annular oil-catching pocket surrounding a part of the compression chamber.

To facilitate the extracting of the oil, I also provide a horizontal partition 21 disposed somewhat above the top 19 of the

compression chamber, which partition forms the bottom of another substantially cup-shaped member having a cylindrical wall 22 provided at its upper end with an outwardly directed annular flange 23 which rests upon a corresponding flange 24 at the upper end of the lateral wall 20. This wall 20 is provided in an upper portion thereof with a port leading to a discharge pipe 4 through which the refrigerant passes to the condenser.

With the parts thus arranged, it will be noted from the arrows 34 in Fig. 2 that the compressed refrigerant discharged through the outlet pipe 18 from the compression chamber is obliged to traverse rather narrow passages formed partly between the horizontal wall portions 19 and 21 and partly between the vertical wall portions 20 and 22, thereby providing a tortuous path adapted to cooperate with the projecting of the issuing gas against the bottom of the partition 21 in causing particles of oil to adhere to the wall portions of this oil separator chamber and to drip into the bottom of the said annular portion of this oil separator chamber. The oil 25 as accumulated there will then be drawn through the oil return pipe 14 into the lower portion of the cylinder whenever the piston is at the top of its travel and the pressure in the crank-case is sufficiently low, as more fully described in the Hanson & Twardowsky Patent No. 1,458,702 of June 12, 1923, on a compressor.

In addition to using the oil separator chamber as means for extracting such particles of oil as gradually enter the compression chamber, I also employ wall portions of this chamber as means for transferring heat from the compressor proper, and from the freshly compressed refrigerant, so as to cool both of the latter and so as to warm the expanded refrigerant before the latter reaches the intake pipe 12 of the compressor. With this in mind, I employ the second cup-shaped casting, of which the partition 21 forms the bottom and of which the cylindrical portion 22 forms a side wall, as the lower part of a storage chamber 26 through which the expanded refrigerant passes to the intake pipe 12, so that this storage chamber is operatively disposed in the intake duct of the compressor. I also desirably provide the said storage chamber with a substantially dome-shaped cover 27 having at its lower end an annular flange 28 secured by bolts 29 conjointly to the flanges 23 and 24 which are respectively at the upper ends of the heretofore mentioned flanges 23 and 24. Then I provide this dome-shaped cover near its top with means for attaching the outlet end of the refrigerating pipe 7 to it and likewise with means for attaching to it the upper end of the intake pipe 12 of the compressor. Thus arranged, the storage

chamber 26 affords a receptacle in which the expanded refrigerant accumulates during the relatively large part of the piston reciprocation in which the connection between the 5 cylinder of the compressor and the intake pipe 12 is closed. By making this chamber of a much greater capacity than the operating portion of the cylinder, and by employing an intake pipe 12 of fairly large bore, 10 I enable the cylinder to be filled quite rapidly with a relatively small reduction in the pressure of the refrigerant within the storage chamber, thereby considerably increasing the efficiency of my compressor over what it 15 would be if the outlet of the refrigerating pipe 7 were connected directly to the intake port 30 of the cylinder.

To further increase the utility of the storage chamber 26, I provide within this a pipe 20 31 leading from the inlet of this chamber (or operatively from the outlet end of the refrigerating pipe 7) to a point near the horizontal partition 21 which forms the bottom of the storage chamber. By so doing, I cause 25 the entering refrigerant to be discharged against this bottom 21 of the chamber, so that any particles of sediment or liquid which have been carried through the refrigerating pipe will be deposited in the bottom 30 of this chamber, thereby securing a clean refrigerating gas for the fresh charge of the compressor.

In addition to serving the above mentioned purposes, the upwardly leading discharge pipe 18 from the compression chamber and the downwardly leading inlet pipe 31 of the storage chamber serve the important purpose of respectively directing the hot freshly compressed refrigerant and the cold 40 expanded refrigerant against opposite faces of the partition 21. Since these parts, and indeed all of the parts illustrated in Fig. 2 of the drawings, are preferably made of metal, they are all of good heat conductivity. 45 Consequently, the partition 21 and the lateral wall 22 of the storage chamber serve as effective means for an interchange of heat between the refrigerant in the storage chamber and that in the oil separator chamber. 50 This interchange of heat is further increased through the heat conduction through the joined flanges which are secured to each other by the bolts 29 and through the outer lateral wall 20 of the oil separator chamber. 55 So that the coldness of the expanded refrigerant in the storage chamber 26 serves to cool both the freshly compressed refrigerant, the compression chamber and the cylinder of the compressor. At the same time, the heat 60 produced in the refrigerant by its compression acts in like manner for warming the expanded refrigerant in the storage chamber 26, the heat transfer being particularly effective through the partition 21 since the 65 hot and cold refrigerant are respectively pro-

jected against the lower and upper faces of this partition and are obliged to travel these faces radially outward of the pipes from which they issue.

In addition to catching and retaining particles of sediment such as occasionally are emitted through the refrigerating pipe 7, the bottom 21 of the storage chamber also catches any particles of liquid carried through the same coil. This liquid is evaporated by the warmth due to the heating of the bottom or partition 21 by the hot compressed refrigerant below the same, and if any considerable quantity of liquid is present, the gaseous refrigerant emitted from the lower end of the pipe 31 will bubble through this liquid and expedite this evaporation. Hence my construction also insures the feeding of the refrigerant to the compressor cylinder in a completely gaseous state.

To increase the effectiveness of the oil separation, I desirably provide a baffle within the oil separator chamber so disposed as to increase the tortuousness of the path which the refrigerant follows in traversing this chamber and also to increase the extent of surface against which particles of oil may be projected. As a simple and effective construction for this purpose, I desirably make the cup-shaped lower portion of the storage chamber somewhat larger in diameter than the top of the compression chamber and provide the bottom of the storage chamber with an annular web 32 extending downwardly below the upper face of the top 19 of the compression chamber and laterally spaced from the outer wall of this chamber. By so doing, I compel the refrigerant after entering the oil separator chamber from the discharge pipe 18 of the compression chamber to flow radially outward from this pipe through a passage of relatively small height and thereafter to be deflected downwardly towards the annular oil-catching channel. In doing so, and in thereafter moving upward between the vertical walls 20 and 22, which walls desirably are separated also by a relatively narrow space, the compressed and hot refrigerant is obliged to pass along both faces of the depending annular web 32. Hence this web serves both as a baffle for facilitating the extraction of oil and as an enlargement of the heat-conducting portion of the storage chamber.

Furthermore, it will be seen from Fig. 2 that a single casting forms the effective partition between the storage chamber and the oil separator chamber, that the parts can easily be machined and assembled, and that each of the three castings forming the head construction of my compressor can first be tested separately as to its soundness and leak-proof condition. However, while I have illustrated and described my invention as used in connection with a compressor em-

ploying features disclosed in two earlier patents, I do not wish to be limited to the use of the various features of my invention in connection with any particular type of 5 compressor construction. Neither do I wish to be limited to the particular details of the shape, construction or arrangement of the various parts as above described, it being obvious that many changes might be made 10 without departing either from the spirit of my invention or from the appended claims.

I claim as my invention:—

1. In a compressor for a refrigerant, a chamber through which the compressed refrigerant is discharged, and a refrigerant storage chamber interposed in the intake duct of the compressor, one of the said chambers having a cup-shaped portion extending 15 into the other chamber and affording a heat-interchanging wall between the two chambers.

2. The combination with a refrigerant compressor of the cylinder type, of a metallic casing mounted on the cylinder end of 25 the compressor in heat conducting relation to the cylinder, a heat-conducting partition dividing the casing into two compartments, and connections for causing the compressed refrigerant and the intake fluid to pass respectively through the two compartments.

3. In a compressor for a refrigerant, a compression chamber into which the compressed refrigerant is discharged by the compressor, a refrigerant storage chamber 35 adjacent thereto and interposed in the intake duct of the compressor, and a third chamber between the aforesaid chambers and through which the compressed refrigerant passes from the compression chamber, 40 the said third chamber being spaced from the first named two chambers by walls of good heat conductivity.

4. In a compressor for a refrigerant, a compression chamber into which the compressed refrigerant is discharged by the compressor, a refrigerant storage chamber adjacent thereto and interposed in the intake duct of the compressor, and a third chamber between the aforesaid chambers 50 and through which the compressed refrigerant passes from the compression chamber, the said third chamber being spaced from the first named two chambers by walls of good heat conductivity and the said walls 55 being shaped to afford a tortuous path for the compressed refrigerant passing through the third chamber.

5. In a compressor for a refrigerant, a compression chamber into which the compressed refrigerant is discharged by the compressor, a refrigerant storage chamber adjacent thereto and interposed in the intake duct of the compressor, and a third chamber disposed between and in heat-conducting relation to the aforesaid chambers

and having the compressed refrigerant passing through it from the compression chamber, the said third chamber having a portion thereof formed for entrapping oil carried into it with the compressed refrigerant.

6. In a compressor for an expansible refrigerant, a chamber forming an enlarged portion of the intake duct of the refrigerator, a second chamber through which the compressor discharges the compressed refrigerant, the said chambers being spaced from each other by a common wall of good heat-conducting material, and connections whereby the compressed refrigerant entering the second chamber and the expanded refrigerant entering the first named chamber are directed respectively against the opposite faces of the said wall.

7. In a compressor for an expansible refrigerant, a compression chamber through which the compressor discharges the compressed refrigerant, a second chamber adjacent to the compression chamber and through which the compressed refrigerant passes from the compression chamber, the compression chamber having a portion thereof extending into the second chamber and the second chamber having an annular web extending into the space between the said portion of the compression chamber and the laterally adjacent wall of the discharge chamber so as to cause the refrigerant to pursue a tortuous path adjacent to both faces of the said web, the said web being disposed in heat-conducting relation to the expanded refrigerant moving toward the intake of the compressor.

8. In a refrigerating system employing an expansible refrigerant, a compressor, a casing associated therewith, a partition of good heat-conducting material dividing the casing into upper and lower compartments; connections whereby the compressed refrigerant is discharged by the compressor into the lower compartment and against the bottom of the partition, and whereby the expanded refrigerant is discharged into the upper compartment and against the top of the partition, and two ducts respectively connecting the upper compartment with the intake of the compressor and the lower compartment with the refrigerating circuit for the refrigerant.

9. In a refrigerating system, a compressor for the refrigerant, a compression chamber in heat-conducting relation to the compressor and into which the compressed refrigerant is discharged from the cylinder, an oil-separating chamber through which the refrigerant is discharged from the compression chamber, and a storage chamber for the expanded refrigerant, the oil-separating chamber having wall portions in common respectively with both of the other two chambers.

10. In a refrigerating system, a cylinder

- type compressed for the refrigerant, a compression chamber in heat-conducting relation to the cylinder of the compressor and into which the compressed refrigerant is discharged from the cylinder, an oil-separating chamber through which the refrigerant is discharged from the compression chamber, a storage chamber for the expanded refrigerant; and a baffle disposed within the oil-separating chamber and in heat-conducting relation to the storage chamber for increasing the interchange of heat between these two chambers.
11. An assemblage as per claim 10, in which the baffle is disposed for compelling the compressed refrigerant to pursue a tortuous path and to flow along both faces of the baffle in passing through the oil-separating chamber.
12. In a compressor for a refrigerator, a compression chamber having an opening in its top, an annular member having a lateral wall of larger bore than the outside diameter of the lateral wall of the compression chamber and an annular wall portion connecting the bottom of the said annular wall to the compression chamber, the said annular wall extending below the top of the compression chamber so that the lateral wall of the compression chamber cooperates with the said annular wall and wall portion in affording an annular pocket, and a member extending across the top of the said annular wall and having a portion disposed above and substantially parallel to the top of the com-
- pression chamber the said annular wall having a refrigerant outlet near its top and the said pocket having an oil discharge outlet at its bottom.
13. A compressor construction as per claim 12, in which the said member has a web extending downwardly into the said annular pocket.
14. A head construction for a refrigerant compressor, comprising a casing member having an inverted cup-shaped bottom forming part of a compression chamber and having an opening in the top of its said cup-shaped bottom, an upwardly open cup-shaped member into which the said inverted cup-shaped bottom projects, a cover for the said upwardly open member, and partitioning member extending across the said upwardly open member, the partitioning member comprising a cup having its bottom relatively close to and above the said opening and having its lateral wall spaced inwardly from the lateral wall of the said upwardly open cup-shaped member; there being a discharge port in the last named lateral wall below the partition and a pair of ports in the said casing member.
15. A compressor head construction as per claim 14, in which the said two members and the cover have flanges conjointly secured to each other.

Signed at Chicago, Illinois, December 22, 1924.

JOHN DUBROVIN.
